UNITED STATES PATENT OFFICE.

JOSEPH S. ROSE, OF PORT CHESTER, NEW YORK.

DIAMOND-TOOL.

1,122,539.

Specification of Letters Patent. Patented Dec. 29, 1914.

Application filed July 31, 1914. Serial No. 854,246.

To all whom it may concern:

Be it known that I, JOSEPH S. ROSE, a citizen of the United States, residing in the village of Port Chester, Westchester county, 5 and State of New York, have invented a new and useful Improvement in Diamond-Tools, of which the following is a specification.

The object of the invention is to provide 10 a diamond tool wherein the diamond is removably and adjustably mounted and to render the tool adaptable to stones of various sizes. To this end a shell is provided having a collar defining a variable orifice 15 in which the stone is held by a clamping member formed to engage with the stone within the collar.

Certain preferred embodiments of the invention will now be described with reference 20 to the accompanying drawings, wherein:

Figure 1 is a side elevation of one of the devices; Fig. 2 is a front view thereof; Fig. 3 is a longitudinal section; Fig. 4 is a perspective view of the removable collar; Fig. 25 5 is a longitudinal section through a slightly modified form; and Fig. 6 is a view partly in section and partly in side elevation of another embodiment of the tool. Fig. 7 is a perspective view of the tapered 30 collar showing a slot in its outer periphery.

In Figs. 1 to 4, 1 is a shell having a threaded bore 2, terminating in front in a tapered bore 3. A removable tapered collar 4 occupies the tapered bore and preferably comprises one of a series adapted to define an orifice of variable size. An internal clamping member 5 has a cylindrical threaded portion 6 to engage the threaded bore and a tapered extremity 7 adapted to 40 enter the collar 4, there to hold the diamond 8 partially projecting from the orifice, as shown in Figs. 1 and 3. The said member in this form is shown as provided with a rearwardly projecting shank 9 having a kerf 10, by which it may be screwed into 45 the shell. A conical recess 12 formed in the forward end of the clamping member cooperates with the collar to form an adjustable cavity for the reception of the diamond and insures a firm holding irrespec- 50 tive of the particular form of the stone. As the latter becomes worn it can be taken out and shifted to a different position, or the orifice can be reduced in size by inserting a 55 smaller collar, or the stone may be replaced

by another, with an appropriate selection of collar.

The form of Fig. 5 is substantially like the preceding except that the shell 1^a is somewhat longer, and the clamping member 5^a is not provided with a rearwardly projecting shank.

Both of the foregoing constructions are machine tools. Fig. 6 shows a hand tool, 65 wherein the clamping member 5^b is formed on or secured to a suitable handle 11, the construction being otherwise like Figs. 1 to 3.

Another feature of my invention is to make the tapered collar 4 with a slot in its outer periphery, as illustrated in Fig. 7. 70 This form of collar would enable the tool to be used for polishing diamonds.

What is claimed as new is:

1. In a diamond tool, the combination of a tapered shell, a tapered collar defining 75 an orifice in the front end of said shell, a clamping member having a tapered end adapted to hold a diamond in said collar, and screw means for causing the member and shell to grip the diamond. 80

2. In a diamond tool, the combination of a shell having a tapered bore at the forward end of its cavity, a tapered collar adapted to occupy said tapered bore, and a clamping member having screw means for 85 forcing it against a diamond in said collar.

3. In a diamond tool, the combination of a shell, a loose tapered slotted collar therein, and an internal clamping member having a conical recess in front to hold a dia- 90 mond in conjunction with said collar.

4. In a diamond tool, the combination of a shell, a loose tapered collar therein, and an internal clamping member having a conical recess in front to hold a diamond in 95 conjunction with said collar.

5. In a diamond tool, the combination of a shell having a threaded bore terminating in front in a tapered bore, a tapered collar occupying said tapered bore, and a screw 100 engaging said threaded bore and having a tapered extremity provided with a conical recess to enter said collar and form therewith a cavity in which the stone is rigidly held.

Dated, June 30th, 1914.

JOSEPH S. ROSE.

In presence of—

CLARENCE G. GALSTON,
G. H. EMPEY.
